UNITED STATES PATENT OFFICE.

ALEXANDER NYMAN, OF NEW YORK, N. Y., ASIGNOR TO DUBILIER CONDENSER CORPORATION, OF NEW YORK, N. Y., A CORPORATION OF DELAWARE.

ELECTRICAL CONDENSER.

Application filed March 11, 1926. Serial No. 93,914.

- My invention relates to improvements in electrical condensers, particularly electrical condensers having a fixed or constant capacity.
- 5 Among the objects of the invention are to provide a condenser which is of simple construction and can be easily and cheaply manufactured; which is strong and practical; which is impervious to moisture; which is of accurate capacity, and has a low power factor; and which is so made that the parts thereof can always be kept under pressure to the required degree and which is, therefore, in practice, as compact as possible.
- 10 Other objects and advantages of this invention will be clear from the following description taken with the accompanying drawings which illustrate the preferred form of my invention. But the disclosure is, of course, illustrative only and I may vary the structure actually shown, without departing from the principle or exceeding the scope of the invention, to the full extent indicated by the broad and general meanings of the terms 15 in which the appended claims are expressed.
- On the drawings,
- Figure 1 is a view showing how the parts of the stack or body of the condenser are disposed with respect to one another when the stack is assembled;
- 20 Figure 2 is a perspective view of a member or section to be disposed on the outside of the condenser and set to retain the parts in their assembled relation;
- 25 Figure 3 is a plan view of one face of the condenser;
- 30 Figure 4 is a side or edge view thereof, seen from the right of Figure 3; and
- 35 Figure 5 is a plan view of the opposite face of the condenser, that is, the face which is the lower face in Figure 3.
- On the drawings, the same numerals identify the same parts throughout.
- I make the body or stack of the condenser 40 out of sheets or elements of suitable insulating or dielectric material, such as mica 1, and sheets or elements of conductive material such as tin-foil 2 and 3. The sheets of foil 2 are of opposite polarity with respect to the sheets of foil 3 and they are, of course, arranged in alternation with the sheets of mica between them, and a sheet of mica on both the top and bottom faces of the stack as usual.
- I have shown in Figure 1 a top plan of the 45 relative positions of the sheets of mica, and the sheets of foil, and while as many sheets of foil may be included as necessary to give the required capacity, the condenser illustrated in the drawings is indicated as having only two sheets of foil 2 and two sheets 50 of foil 3. As Figure 1 shows, the sheets of foil 2 are at right angles or transverse with respect to the sheets of foil 3, and two sets or groups of foils are arranged diagonally with respect to the sheets of mica 1. Specifically, 55 the sheets of foil 2 extend from the upper left hand corner of the mica sheets in Figure 1, to the lower right hand corner; while the sheets of foil 3 extend from the upper right hand corner across the mica sheets, and to 60 the lower left hand corner thereof. The ends of the sheets 2 and 3 project beyond the adjacent edges of the mica sheets 1 to facilitate uniting the elements 2 and 3 to the opposite terminals of an electric circuit. 65 When this stack is assembled, it can be treated in any manner desired, as by pumping out the air between the mica sheets and the foils and then impregnating the stack with wax or some other insulating material. 70 The sheets of foil and mica in the stack are then secured together permanently in the required relation by means of a pair of clamping members indicated at 4 and 4', one of 75 these clamping members overlying and engaging one face of the stack and having portions which are bent around opposite sides or edges and over and down upon the opposite face; while the other clamping member or section overlies and engages with the opposite face and has portions which extend 80 across the remaining sides or edges of the stack and are bent down into engagement with the first face. As shown in Figures 3 and 4, the two sections 4 and 4' are arranged 85 transversely of each other, so that if the section or clamp 4 grips the top and bottom edges of the condenser in Figure 3, and engages the face which is the lower face in that figure, the other clamp 4' will overlie the upper face and it will grip the two edges which are the opposite side edges of the condenser. 90
- As shown in Figure 2, the clamping member 4 has portions 5 at each end which when the clamp is put upon one face of the stack 95 of the condenser, can be turned down tightly against the opposite face. These portions or flanges 5 are connected by portions 6 to the main part 7 of the clamp 4 which has the form of a plate or web. The clamp or section 100
- 105
- 110

4' has corresponding parts indicated by the numerals 5', 6' and 7', and is shaped in every way similar to the clamp 4. This clamp 4 further is so shaped, that the parts 5 and 5 6 at one end are flush at one extremity with the adjacent side edge of the plate 7, but extend beyond the opposite side edge; while the portions 5 and 6 at the other end of the clamp have one extremity flush with this opposite side edge, but extend beyond the first side.

Hence, when the clamp is applied to one face of the stack of the condenser, it engages that face on the central portion but leaves 15 uncovered areas adjacent diagonally opposite corners of the stack against which the portions or flanges 5 of the clamping section on the opposite face can be pressed down into contact. For example, the clamp 4' on 20 the upper face of the condenser as shown in Figure 3 leaves uncovered portions adjacent the upper left hand corner and lower right hand corner for the flanges 5 of the clamp 4 upon the lower face, and similarly, 25 there are uncovered portions on the lower face of the stack against which the flanges 5' of the clamp 4' can be pressed. When the stack is engaged by both the clamps, and the flanges 5 are caused by pressure to grip 30 the edges of the condenser to hold the clamp in place, the stack of the condenser is in effect covered or clad with the two clamping sections 4 and 4', but the flanges 5 of each clamp are separated by an L-shaped space 35 8 from the sides of the web 7 of the other clamp on both faces of the condenser. Hence, if the projecting portions of the foils 3, for example, are turned over against the outside of the stack and gripped by the flanges 40 5' of the clamp 4', and if the projecting ends of the foils 2' are also turned over against the outside of the stack and gripped by the flanges 5 of the other clamp 4, then the clamp 4' will be connected to the elements 3 and the clamp 4 will be connected 45 to the elements 2. As the two clamps can most advantageously be made of metal, it is only necessary to connect the two clamps to the opposite terminals of an electric circuit 50 to unite the condenser to the circuit in which it is to operate.

As shown in Figure 4, I may use covered plates of insulation, such as bakelite 9, on the two opposite faces of the stack of foils 55 2 and 3, and mica sheets 1. The two parts 6, 6 and 6', 6' of the clamping sections have projections 10 which may be perforated to enable a wire to be joined to them. Hence, the condenser will have means at each corner 60 to enable it to be joined in each circuit, and if a wire be fastened to any two adjacent projections 10, the two opposite terminals of the condenser will thus be joined to the two poles of an electric circuit and the condenser 65 can thus most easily be united in circuit by

means of the projections or lugs at the corners. Each plate 7 and 7' of the two clamps may have a rib 11 to reenforce the clamp and make it stronger and stiffer.

A condenser so made can very easily be 70 assembled and will give the required degree of pressure to hold the sheets of foil and mica in contact over substantially their whole area. At the same time, the covering clamps 4 and 4' impart great strength to the condenser and enable it to resist damage and the effects of rough handling. It is quite 75 cheap to make; the capacity can be kept fixed and accurate; it gives a low power factor in practice; and the entrance of moisture 80 in between the sheets of foil and mica, is effectively prevented. Likewise, the parts are very easy to assemble and the two clamps afford as much pressure as is required to make the finished condenser compact and to 85 hold parts in the required positions.

It should be noted that there is no plane of symmetry about which the various parts of the condenser are arranged. The various parts are symmetrical with respect to a central point or with respect to a line or axis perpendicular to the laminations in the stack and located at the center thereof. Looking at Fig. 3 and considering any given clamp, it will be seen that the clamp extends in an anti-clockwise direction along the respective side of the stack to the corner of the stack which it engages, or, considering the corners as starting points and again looking at Fig. 3, the clamps all extend in a clockwise direction from their respective corners of the stack along the respective edges that the clamps embrace. Superficially the pattern of the condenser bears a strong resemblance to the well known "swastika" design.

Having described my invention, what I believe to be new and desire to secure and protect by Letters Patent of the United States is:—

1. A condenser comprising elements of conductive material and elements of dielectric material separating said conductive elements, the latter being in diagonal position with respect to the dielectric elements.

2. A condenser comprising conductive elements of opposite polarity in transverse position, and sheets of insulating material between said elements, the conductive elements being diagonal with respect to said sheets of insulating material.

3. A condenser comprising a stack containing conductive elements of opposite polarity, sheets of insulating material separating said conductive elements, the elements of one polarity projecting from the sides of the stack adjacent diagonally opposite corners and the elements of opposite polarity being arranged transversely of the first-named conductive elements, and having their ends projecting from the stack adjacent diag- 120 125 130

onally opposite corners; and clamping members for the opposite faces of the stack, each of said members engaging the projecting ends of the conductive elements of one polarity, whereby the condenser can be connected into circuit through said clamps.

4. A condenser comprising a stack of conductive elements separated by insulation, and a clamping member for the stack comprising
10 a plate with flanges along the opposite ends to grip the edges of the stack, the flange at

one end extending beyond one side in one direction, and the flange at the opposite end extending beyond the opposite side of the clamp in the opposite direction, together with portions connecting said flanges to the plate, each of said portions having a connector lug or projection, said lugs extending in opposite directions. 15

In testimony whereof I affix my signature.

ALEXANDER NYMAN.
